Primary Examiner—Gary D. Watson
Attorney, Agent, or Firm—Woodard, Emhardt, Naughton, Moriarty & McNett**[57] CLAIM**

The ornamental design for a fibreboard chair with arms, as shown and described.

DESCRIPTION

FIG. 1 is a perspective view of a fibreboard chair with arms showing a typical embodiment of the new design;

FIG. 2 is a front, elevational view of the fibreboard chair with arms;

FIG. 3 is a left side, elevational view of the fibreboard chair with arms. The right side, elevational view is a mirror image of the left side, elevational view and therefore is not separately shown;

FIG. 4 is a back side, elevational view of the fibreboard chair with arms;

FIG. 5 is a top, plan view of the fibreboard chair with arms; and,

FIG. 6 is a bottom, plan view of the fibreboard chair with arms.
